UNITED STATES PATENT OFFICE

2,594,614

HAMMER POCKET DEVICE

Harvey B. Behnke, Appleton, Wis.

Application January 10, 1951, Serial No. 205,394

2 Claims. (Cl. 2—248)

1

This invention relates to a hammer pocket device.

It is to be understood that when people place hammers in their pockets the pocket is often torn, or the hammer becomes entangled in the pocket which is very unsatisfactory to the user.

Therefore, one of the objects of this invention is the production of a device which will permit the easy placing of a hammer in the pocket of preferably a carpenter, and allowing the hammer to be quickly removed when desired.

Another object of the invention is the construction of a pocket device for holding a hammer, or hatchet, which device is constructed to fit the curvature of the body of the carpenter, whereby the device is used with no discomfiture.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a perspective view of a device constructed in accordance with this invention.

Figure 2 is a fragmentary sectional view of a garment, showing particularly a pocket thereof, with a device in vertical section therein.

Figure 3 is a fragmentary view of a garment, such as an overall, showing one of the pockets thereof in partial section, and the device of this invention in the pocket, as well as a hammer in the device.

Referring to the drawings, in which the preferred embodiment of this invention is illustrated, 1 designates the flat body of the device which is provided with two integral sides 2 that extend at right angles to the flat body 1. Integral with the body 1 and sides 2 is a flat bottom 3. The bottom 3 is curved at 4 on its outer edge to fit the body of the user, whereby the device is very comfortably employed.

In Figure 2 the device is shown in the pocket 5, while in Figure 3, the device is shown with a hammer 6 therein.

In actual use the hammer 6 is slid down against the body, hitting no edges, and moves into a rest position, as shown in Figure 3. The device protects the outside of the overall pocket, and holds the pocket in an open position, ready to receive the tool when the user is temporarily through with using the same.

The device permits the user to have free move-

2

ment as the device holds the tool in a satisfactory position for such movement.

While I have described the preferred embodiment of the invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. As a new article of manufacture, a one-piece hammer pocket device, comprising a flat vertical body provided with two parallel flat sides, said sides being at right angle to said flat vertical body, a flat bottom at right angle to said flat vertical body and said parallel flat sides, and said flat bottom being curved inwardly on its outer edge, whereby said curvature fits the shape of the buttocks of the human body when the device is in use.

2. In combination with the hip pocket of a carpenter's overalls; of a hammer-head holding device in said pocket comprising a flat body substantially the width of said pocket and bearing against the outer portion of said pocket, parallel side portions integral with said flat body, said side portions provided with outer vertical edges bearing against the inside pocket, a flat horizontal bottom integral with said side portions and flat body, and said bottom being curved inwardly on its outer edge to receive a portion of said pocket and to fit the buttock of the wearer of the overalls.

HARVEY B. BEHNKE.
